UNITED STATES PATENT OFFICE.

CHARLES E. OATHOUT, OF CLEVELAND, OHIO, ASSIGNOR TO KAYNEE COMPANY, OF CLEVELAND, OHIO, A CORPORATION OF OHIO.

BLOUSE.

Application filed June 5, 1925. Serial No. 35,034.

The present invention, relating as indicated to blouses, has more particular regard to the arrangement of the cords or shirr-strings whereby the diameter of the lower edge of the blouse may be adjusted. The object of the invention is the disposition in a blouse, or similar garment, of one or more cords in such fashion that there are no loose ends to become lost in the hem of the garment, while at the same time the adjustment may be effected by drawing and tying the cord without the use of buttons, hooks or the like which are obviously objectionable in adjustments of this sort.

15 The present invention is similar in a general way to that shown in U. S. Letters Patent No. 983,551 but permits the use of a plurality of cords, if desired, so arranged that when they are pulled to reduce the 20 diameter of the lower edge of the blouse, this lower edge portion may be arranged in symmetrical pleats spaced equidistant from the center line or open front of the blouse thus maintaining the neat appearance of the 25 garment. To the accomplishment of the foregoing and related ends, said invention, then, consists of the means hereinafter fully described and particularly pointed out in the claim.

30 The annexed drawing and the following description set forth in detail certain structure embodying the invention, such disclosed means constituting, however, but one of various structural forms in which the principle of the invention may be used.

In said annexed drawing:—

Fig. 1 is a front elevational view of the blouse more or less diagrammatic in character in showing the cord in position for adjustment. Fig. 2 is a view similar to Fig. 1 but showing the cords adjusted to reduce the blouse diameter. Fig. 3 is a broken elevational view showing one of the cords on an enlarged scale. Fig. 4 is a rear elevational view of one of the cords showing its arrangement in the hem of the blouse. Fig. 5 is a diagrammatic sectional view showing the arrangement of the cords and the hem of the blouse in the extended position of the blouse, and Fig. 6 is a view similar to Fig. 5 but showing the cord drawn tight to reduce the blouse diameter drawing the ends of the cord toward and behind the eyelet.

I have shown the present invention as applied to the ordinary form of the blouse as

manufactured for children but it is not intended to restrict the application of the invention to any particular garment. In the device illustrated, the blouse 1 is open down the front and normally closed by series of buttons 2 and button holes 3, and this blouse is provided along its lower edge with the usual hem 4. The adjusting means in the present blouse consist of a plurality of cords 5 which have their ends 6 sewn into the line of stitching 6^a forming the hem 4, and having the doubled end 7 of each cord extending through a suitable eyelet 8 formed in the hem of the blouse and spaced equidistantly between the points at which the ends 6 of the cords are sewn to the hem. In adjusting the blouse diameter, the looped end 7 of the cord will be drawn through the eyelet, the ends of the cord drawing the attached portions of the garment toward and behind the eyelet until the hem of the blouse assumes the position shown in Figs. 2 and 6, and this looped end will then be knotted as at 10 on the outside of the eyelet which is small enough in diameter so that the knotted portion 10 of the cord will not draw therethrough. In this way the front of the blouse is formed with two pleats 11 symmetrically disposed to the center line or open front of the blouse.

The amount of adjustment obtained depends upon the distance between the ends 6 of the cords where they are sewn into the hem of the blouse and the number of such cords that are employed, however, it has 40 been found in general use that in a blouse type of garment two such cords are sufficient, each cord giving normally about 4 inches of adjustment. The use of cords of this length 45 symmetrically placed in respect to the center lines of the blouse enables the blouse to be adjusted readily and symmetrically so that uneven bunching around the hem is avoided and at the same time there are no free ends 50 of the cords which may become lost in the hem of the garment and the looped end is kept short so that a long dangling string 55 is avoided, as is commonly the case where a draw string is employed throughout the hem of the garment.

Other modes of applying the principle of my invention may be employed instead of the one explained, change being made as regards the construction herein disclosed, provided the means stated by the following

claim or the equivalent of such stated means be employed.

I therfor particularly point out and distinctly claim as my invention:—

- 5 A garment having take-up means adjacent its lower edge, said means comprising an eyelet formed through said edge, a cord attached at its ends to the rearward face of said edge at points equidistant from said eyelet with the length of cord greater than 10 the distance between said points of attach-

ment to provide a loop to be engaged through said eyelet and adapted when tensioned to draw the ends of said cord and the attached garment toward and behind said eyelet to form a box pleat of any desired size and to maintain said adjustment by knotting the looper portion of the cord immediately in front of said eyelet.

Signed by me this 2nd day of June, 1925.

CHARLES E. OATHOUT.
